UNITED STATES PATENT OFFICE.

ROBERT JAVAULT, OF PARIS, FRANCE, ASSIGNOR TO SOCIÉTÉ FRANÇAISE DES FILMS & CINÉMATOGRAPHES, "ECLAIR," OF PARIS, FRANCE.

APPARATUS FOR DEVELOPING AND WASHING CINEMATOGRAPHIC FILMS.

1,141,464.

Specification of Letters Patent. Patented June 1, 1915.

Application filed December 8, 1911. Serial No. 664,871.

To all whom it may concern:

Be it known that I, ROBERT JAVAULT, of Paris, France, have invented a new and useful Improvement in Apparatus for Developing and Washing Cinematographic Films, which is fully set forth in the following specification.

For developing and treating cinematograph films or pelicles or strips (I will refer to them as films) various forms of apparatus have been used comprising a series of vats containing the treating and washing liquids in which the film is unrolled and treated. The film must be so arranged as to present the greatest possible length in each vat or receptacle, this being to the detriment of the guiding and driving of the film which can only take place at a small number of points and has the disadvantage of causing excessive torsions and strains which effect a rapid wearing out of the film.

The apparatus which forms the subject of this invention has been designed to insure a perfect guiding and driving of the film in the various treating receptacles. For this purpose each receptacle is traversed at its upper part by a shaft carrying a series of alternately arranged guiding and driving rollers, while the lower part of each vat is provided with guide and tension rollers arranged in sets, in one of which the rollers are mounted in stationary bearings and in the other set the rollers are mounted in movable bearings, the rollers in both sets being arranged to twist the film back and forth between the sets of rollers; and for this purpose the axes of the two sets are preferably at right angles to each other. The film passes successively in each vat over an upper guiding roller, then over a stationary lower roller after undergoing a twist through 90° and thereupon ascends over a driving roller after having been subjected to a second twist which brings it back to an upper roller in its original position to descend again onto a yieldingly mounted roller which imparts to it the proper tension and so on until it reaches the last upper roller which conducts it to the next vat. This arrangement enables a great length of film to be treated in each receptacle, and a guiding and driving to be obtained that will be sufficient to avoid any appreciable wear of the film.

The invention will be described with reference to the accompanying drawings in which—

Figures 1 and 2 show respectively a longitudinal section and a transverse section of a vat suitable for treating and washing films. Fig. 3 shows a modification of the lower part of the said vat. Figs. 4, 5, 6, 7, and 8, illustrate on a larger scale, details of the guiding and driving members. Figs. 9 and 10 show diagrammatically, on a small scale, in elevation and plan respectively an installation for treating films.

The film X which has just been exposed, must in order to be treated pass through a series of receptacles containing the liquids requisite for these operations. Each vat or receptacle A (Figs. 1 and 2) made of any suitable material such as wood or stoneware is traversed at its upper part by a shaft a to which a rotary motion is imparted, which shaft carries two sets of alternated rollers b and c, the rollers b being mounted loosely thereon, and acting solely as guides while the others c are keyed on the said shaft a and carry sprockets for propelling the film forward. The shaft a revolves in bearings d kept in position by supports e arranged outside the vat, the said bearings also maintaining a rod f placed in the lower part of the vat parallel to the shaft a.

On the rod f are mounted in two different planes stationary mounted rollers g and movable rollers h which are yieldingly supported. These rollers g and h have their axes arranged at right angles to the axes of the upper rollers b and c and act as guides for the film X returning it at the lower part of the vat.

The strip or film X enters the vat on a smooth upper roller b shown at the left in Fig. 1 and descends to a stationary mounted guiding roller g after having undergone a twist of 90°. The last named roller returns the film to a driving roller c and the film, after a further twist of 90° in reverse direction, is again returned to a guide roll. This twist permits of guiding the film at the upper and lower parts of the vat while driving the same a number of times in the same vat or receptacle, thus avoiding repeated pulls and the shearing stresses due to an insufficient driving which would cause a con-

tinual wear and even a rupture of the film. Moreover the emulsined surface of the film is kept free from rubbing on the various rolls or rollers. On leaving the driving roller *c*, the film again descends to the lower part of the vat where it passes over a tensioning roller *h*, whereupon it again ascends to pass over a smooth roller *b*, the passage of the film from the upper rollers of the vat 10 to the lower rollers and vice versa taking place with a 90° twist of the film. In order to further increase the smoothness of the motion, the driving rollers *c* are preferably constructed in several parts as shown in Figs. 15 4 and 5, where two metal sprocket disks *i* are shown keyed on the shaft *a* and kept at the required distance apart by a sleeve *j* surrounding the shaft *a* and keyed thereon. Between the disks *i* inclosing the roller *c* 20 and the rollers *b* and loose on a sleeve *k* keyed on the shaft *a* are inserted washers *l* of fiber or ebonite revolving freely on the said sleeves *j* and *k*. As the perforations of the strip do not always properly register 25 with the sprockets of the driving disks in existing apparatus tensile stresses are produced on the film causing its injurious wear. In the hereinbefore described arrangement the loose washers *l* will follow the motions 30 of the film. The liquid of the vat or receptacle penetrates into the interstices between these various parts of the driving rolls *c* and plays somewhat the part of a lubricant while removing the waste caused by the wear 35 of the ebonite or fiber on the metal.

The movable lower rollers *h* which insure the tension of the film are preferably yieldingly mounted in any suitable manner, as shown for example in Figs. 6, 7 and 8 in 40 which their shafts *m* are secured to levers *n* secured to shafts *o* capable of turning in bearings on the rod *f*, the movements of the levers *n* being limited by projections *p* engaging in slots *q*. On each shaft *o* is keyed 45 a small pulley *r*. A blade spring *x* connects the pulleys *r* in pairs so as to return to their lower position the rollers *h* which have been raised for laying on the band or film.

I will now explain the operation of the 50 device thus far described. As shown in Fig. 9 and 10, the apparatus for the treatment of films comprises seven receptacles or vats and a drier through which the film passes in succession, namely a vat *A*¹ containing the developing bath, a vat *A*² for washing, a hyposulfite vat *A*³, two vats *A*⁴ and *A*⁵ for containing a full supply of water for washing with a sprinkling device *B* and *B*¹, one vat *A*⁶ for dyeing and a last washing vat *A*⁷ with sprinkling device *B*² and a suitable drier. The various water washing vats communicate at their lower part with any known drain system which is intended to collect the passing water which is constantly 60 renewed by the sprinklers *B*, *B*¹ and *B*².

When the films are to be treated so as to remain black (or uncolored), the two vats *A*⁶ and *A*⁷ are not needed and the water film goes directly into the drier. The toning frame *A*⁶ can be replaced by a toning frame in case black toned films are to be dyed. Two supplementary frames, one for the toning and the other for the washing, should then be inserted between the two vats *A*⁵ and *A*⁶. The sensitized film is uncoiled from a coil *C* and reaches the first vat *A*¹ after having passed over two power driven rolls *s*. Rotary motion is transmitted from the shafts *a* of the vats by endless chains actuating pinions or pulleys *u* keyed on the ends of the shafts *a* and yieldingly mounted on the rollers *v* insuring the tension of these chains. This mode of driving permits of adding or withdrawing one or more vats without stopping of time.

To enable a film to be passed from one vat to the next on a smooth roller *b* of the apparatus, as shown in Fig. 10, the film passes over the shaft *a* under good conditions and without any torsion of the film, it is necessary that the film pass off the lower series of rolls, the movable roll *h* and up to a smooth roll *b* of the successive vats. Since the film passes through successive vats in opposite directions as shown in Fig. 10, the terminal movable roll *h* in one vat will be located in the vat at the extreme right and in the vat at the extreme left as appears in Fig. 1.

What I claim is:—

1. In apparatus for treating cinematic graphic films or the like, the combination of a vat, a shaft provided with idle rollers, drive rolls alternating with each other, mounted in said vat, a support in said vat, and a plurality of rolls mounted thereon, having their axes of rotation at right angles to that of said shaft whereby the film is twisted and untwisted through 90° and maintained in alinement with the drive rolls without side thrust.

2. In apparatus for treating cinematic graphic films or the like, the combination of a vat, a shaft provided with idle rollers, drive rolls alternating with each other, mounted in said vat, a support in said vat, and guide rolls mounted thereon, some of which are stationary mounted and others yieldingly mounted to act as tensioners, and having their axes of rotation at right angles to that of said shaft whereby the film is twisted and untwisted through 90° and maintained in alinement with the drive rolls without side thrust.

3. In apparatus for treating cinematic graphic films or the like, the combination of a shaft provided with film guiding and driving rolls mounted thereon, each drive roll having sprocket disks fast to the shaft and adapted to engage perforations in the film, and loosely mounted side washers adjacent said disks adapted to follow the motion of the film.

movement of the film and prevent wear of its edge portions.

4. In apparatus for treating cinematographic films or the like, a receptacle, and means therein for advancing the film while twisting and untwisting said film during such movement.

In testimony whereof I have signed this specification in the presence of two subscribing witnesses.

ROBERT JAVAULT.
